REFRACTORY TILE

Robert W. Jones, Birmingham, Mich., assignor to Bigelow-Liptak Corporation, Detroit, Mich., a corporation of Michigan

Filed Oct. 2, 1964, Ser. No. 82,005

Term of patent 14 years

(Cl. D81—25)

I claim:

The ornamental design for a refractory tile, as shown and described.
